J. KEITH.

POSTAGE STAMP ATTACHER AND RECORDER.

No. 548,880.

Patented Oct. 29, 1895.

The diagram illustrates a complex industrial vessel or reactor assembly. It features a central vertical column with a grid pattern, labeled 'S'. Above this grid, the vessel is divided into sections labeled 'B', 'B'', 'B''', 'B''''', and 'B'''''. A horizontal plate labeled 'A' is positioned above the top section. A horizontal pipe labeled 'M' extends from the right side of the vessel. The bottom section of the vessel is supported by a base structure with various bolts and nuts, labeled 'N1' through 'N6'. The entire assembly is contained within a rectangular frame.

UNITED STATES PATENT OFFICE.

JOHN KEITH, OF OTTAWA, CANADA.

POSTAGE-STAMP ATTACHER AND RECORDER.

SPECIFICATION forming part of Letters Patent No. 548,880, dated October 29, 1895.

Application filed April 1, 1895. Serial No. 544,113. (No model.)

To all whom it may concern:

Be it known that I, JOHN KEITH, of the city of Ottawa, in the county of Carleton and Province of Ontario, in the Dominion of Canada, have invented certain new and useful Improvements in Automatic Postage-Stamp Attachers and Recorders; and I do hereby declare that the following is a full, clear, and exact description of the same, reference being had to the accompanying drawings, forming a part hereof.

My invention, which will be hereinafter fully set forth and claimed, relates to devices for holding and attaching postage stamps to envelopes and other objects and recording the number used.

The object of my invention is a machine, device, or apparatus adapted to receive and hold a series of connected postage stamps and to detach and secure them upon envelopes and other objects after moistening the latter by means of simple movements without handling them, also to record the number used.

Figure 1 is a top view of my new machine, the stamping-table being removed and parts being in section. Fig. 2 is a transverse section on line 2 2, Figs. 1 and 5. Fig. 3 is a perspective obverse and rear view of the table-support. Fig. 4 is an elevation of the table and adjoining portion. Fig. 5 is a longitudinal section on line 5 5, Figs. 1, 2, 6, and 7, parts being broken out. Fig. 6 is an elevation of the front end. Fig. 7 is a sectional end elevation immediately at the rear of the front plate, being a section on line 7 7, Fig. 5. Fig. 8 is a detail in perspective, showing the mechanism for turning the disk. Fig. 9 is a detail showing parts of the disk in section. Fig. 10 is a detail showing one of the spring-pins and cam. Fig. 11 is a cross-section at line 11 11, Fig. 5, showing the knife and its operating-spring. Fig. 12 is an elevation of the mechanism immediately at the rear of the dial, showing the spring and gear turning the central spindle and moving the sheet of stamps longitudinally. Fig. 13 is an elevation of the rear end, showing the dial indicating the number of transverse strips of stamps used. Fig. 14 is an elevation of the rear end immediately at the rear of the wheels and showing the mechanism for releasing the gear.

Upon a base A, Figs. 1, 4, 5, 6, and 7, is se-

cured a stationary cylindrical body B, with a rotary end C and a spring-support N for a movable table T. The upper surface of the table when fully raised is nearly level with the lowest point of the circumference of the body B, the latter being sufficiently raised on stands on the base. The cylinder B, which may be solid or composed of a shell b and ends b', as shown in Figs. 1, 2, and 5, has its circumference equal a multiple of the size of stamps to be used. I prefer it equal to fourteen stamps, so as to hold a sheet of ten rows and leaving a space of four at the bottom unoccupied. Its length is immaterial, being made ample for the length of a sheet of stamps. In working a sheet S of stamps is placed upon this cylinder from the top, so that the spare space between the opposite edges is at the bottom, and a gage b'''', Fig. 2, is secured to the rear side of the cylinder to receive the edge of the sheet on that side in a true position.

A transverse or circumferential gage B', Figs. 1 and 5, is provided at the rear end of the cylinder and adapted to receive the rear edge of the sheet and propel it along the cylinder. For this purpose an arm B'' is secured to it, Figs. 2 and 5, which passes through a slot B⁷ in the shell b to the center of the cylinder, where it forms the nut of a screw B''', passing through the same, and which, being journaled in the ends of the cylinder, is adapted to propel it forward and backward. A casing or cover B⁴ is provided, completely inclosing and protecting the stamps placed upon the cylinder. That shown in Figs. 1, 2, 4, 5, 7, and 11 is in two halves hinged low down at the sides and joined at the top, being there provided with lugs b⁴, which may be provided with means for locking them.

The front end of the cylinder b' has its journal for the screw B''' formed into a forwardly-extending sleeve b'', the front end of which passes through and is secured to the front-end plate B⁵, which is secured to the base A. An end plate B⁶, secured to the base, carries the screw and cylinder at the rear end, the rigid connection between the sleeve b'' and front plate B⁵ giving rigidity to the cylinder. (See Fig. 5.)

Upon the sleeve B'' is journaled a disk or end C of the same diameter as the cylinder and so close to it as to leave merely room for

a thin knife D, Figs. 5 and 11, to move between the two ends. Said knife consists of a thin blade journaled by a hub d upon the sleeve b'', projecting beyond the surface of the cylinder and cover, so as to afford a handle d', and having a sloping cutting-edge d'' intersecting the surface of the cylinder and having the effect of a draw cut. This is for the purpose of cutting off a transverse row or strip of stamps that has been passed upon the edge of the disk C, so that the perforated line coincides with the joint between the disk C and the adjacent cylinder end. The operation is performed by drawing the knife by the handle from rear to front, a spring D', coiled and secured upon the sleeve b'' in a recess in the disk C and having the end secured to the knife, moving the latter back ready to be again drawn forward.

20 The disk C carries at its front face equidistant from the center and near its periphery a series of equidistant pins C' in holes sunk in the disk and projected forward by springs C'', inserted between the ends of the pins and the bottom of the holes, one for each stamp-space on the surface of the disk, as shown in Figs. 5, 7, 8, and 9. The projecting part of each pin has secured to it a downward-projecting pin c', forming a shoulder thereon, bent at 25 a right angle back toward and projecting into a hole in the disk, in which it may slide freely and forming a guide to the pin C', which also slides freely in its own hole in said disk and is guided therein. The front ends of the pins 30 C' bear plainly-marked numerals in proper succession, corresponding to the number of stamps in one strip—say from "0" to "9," "1" to "10," or "1" to "14"—and said ends so marked bear against the inner face of the 35 front-end plate B⁵. In one place of the path of said pins, preferably at the top, a perforation b⁵ is provided, into which each pin coming opposite is pressed by the spring C''. Said perforation may be provided with a bezel 40 and glass or other transparent insertion b⁶ at the front, so that the perforation forms a recess, however.

When the disk C is being rotated, the first pin C' coming opposite the perforation b⁵ will 45 pass into it, stop the further rotation of the disk, and exhibit the number of its face. For the purpose of disengaging such pin a lever E is attached to a spring drum or hub e, journaled upon the sleeve b'' and containing a 50 spring E', having one end secured to said sleeve and the other to said drum and tending to turn the lever toward the rear, the latter being flat and close to the inner face of the end plate and the upper end projecting to afford a 55 finger-hold e' above the surface of the disk and its cover. To the inner face of said lever is secured a segmental finger e'', projecting toward the front between the front plate B⁵ and the guide-pins c' below the pins C' and 60 wedge or cam-shaped, being of such a breadth at the heel that in being drawn forward and bearing on the pin c' it will press the pin C' so

far into the disk C as to withdraw it from the perforation b⁵ and finally keep the pin c' in engagement in a notch e''', as shown in Fig. 70 10. To accomplish this the lever E must be drawn toward the front against the pressure of the spring E', and when it has arrived in the position shown in Fig. 10, the pin in the perforation b⁵ being released, it is let go and the spring E' turns it backward, together with the disk C, the latter being moved by the disengaged pin c', against which the heel of the cam e'' presses. The disk C is thus turned the space of one stamp when the next forward 75 15 pin C' has arrived opposite the perforation b⁵, engages it, and stops the further progress of the disk. To steady the disk C while the lever E is being manipulated and limit its forward motion, a spring-detent e'''' is provided on 80 the inner face of the front plate, Figs. 6 and 9, for one of the rearward pins C', allowing said pins to pass rearwardly over it, but striking it if the lever E should accidentally tend to turn it forward.

At the rear is a small endless apron F, Fig. 7, of the same width as the edge of the disk C, pressed against the surface of the edge. It passes over an upper roller F' a little above the line of the gage b''' and a small one F'' near the center of the disk at the bottom. Said rollers are journaled in a box or frame F''', which is carried by a spring f''', secured to the base or some intermediate object, such as the block A', which spring presses the two rollers 90 95 against the edge of the disk. Means are provided on the frame F''', such as the handle f', to press it down and cause an open space between the apron and the surface of the disk when pushing a new strip of stamps upon the 100 disk. These rollers and apron have the object of holding the forward end of the strip tight against the rotary disk and cause the former to travel with the latter and to present the forward end—i. e., one stamp—under the center 105 110 of the disk.

The upper surface of the disk C, so far as the strip of stamps extends, is covered in and protected by a cover B⁷, secured to the front plate B⁵ as a continuation of the cover B⁴ of the cylinder. In order to present a clear space under the center of the disk C, the front-end plate B⁵ is shaped to follow the contour of the disk past that point, so that its connection with the base is rearward, as shown in Fig. 6. 115 120

To the front of the front plate B⁵ and between the center and the perforation b⁵ is pivoted at G' an arm G, the upper end of which is linked at g to the lever E, and the lower end carries a sponge or brush g', bent 125 to extend across the surface of the disk C. That part g'' of the said arm immediately on and above said sponge or brush is made tubular to serve as a reservoir and communication therewith for some liquid, the transverse limb g''' being perforated, as shown in Figs. 5 and 6. This sponge or brush g' moves with the lever E, sweeping close to the lower periphery of the disk C and under its center, 130

and is adapted to moisten the envelope or other object at the spot where the stamp is to be affixed.

The screw B'''', having the function of propelling the sheet or remainder of the sheet of stamps S along the cylinder B and bringing a new strip upon the disk C when one has been consumed, must have such a pitch that a certain measured turn propels the arm B''' 5 exactly the width of a strip. The screw may be turned by hand at the rear end by means of a suitable key or by any suitable mechanism, one such being shown in Figs. 5, 12, 13, and 14. In this instance the pitch of the screw B''' is such that one revolution moves the arm B''' the width of a strip of stamps. The end of the screw carries a pinion h', gearing into a wheel h, ten times its size, (presuming that a sheet of ten strips is to be dealt with,) so that for every revolution of the wheel h the screw B''' will make ten. The arbor H upon which the wheel h is mounted, is journaled in the end plate B⁶, and a plate I, forming part of a casing for the mechanism, and also a dial-face bearing numerals corresponding to the number of strips in a sheet—say “0” to “9”—and passing through said dial, carries an index hand or finger H', and has its ends squared to adapt it for the 20 application of a key for winding. Said arbor has coiled upon it a spring H'', having one end secured to a pin h''' and tending to turn said wheel and arbor. The latter has also secured upon it a disk h'', with ten 25 notches 5, Fig. 12, and above it is a hooked detent K, pressed upon the rim of the disk and into one of the notches by a spring k. A lever L reaches with one arm under the detent K, being so shaped as to lift it when the other arm is depressed, pins l l' limiting the downward movement of both arms.

A vertical pusher or presser M, projecting at the top above the casing, so as to allow it to be pushed down, is guided at the upper end by a pivot-pin m' in a slot m, at the lower end by a hooked pin m'' at the side of the lever L, and at the opposite or outer side and between the two guides by a spring M', pressing it against the other two. Above the hooked pin m'' 45 and on the edge which bears against the pin by the pressure of the spring is a wedged-shaped projection or incline m''', adapted, when the pusher is being pressed down, to cause it to deviate against the pressure of the spring M' by bearing against the pin m'' and slipping off the end of the lever L, care being taken that this does not occur before the detent has been disengaged from one of the notches 5, but immediately afterward. The 50 lever L, being thus released the moment the detent K is released from the notch, ceases to control the detent and allows it to again press upon the edge of the disk h'', ready to engage the next notch. The spring M' presses the 55 pusher not only against the guide m'', but also lifts it as soon as the pressure upon it

from the top is relaxed. Thus it will be seen that a touch of the presser M causes the spring H''' to turn the screw B''' sufficient to move a new strip of stamps on the 60 disk C, which now requires to be severed from the sheet, its end having first been admitted between the disk and the apron F at the roller F' by depressing the rod f''. To hold the corner of the sheet it is clamped in 65 the gage b''' by a spring-button b'' passing through the cover B⁴. When the arbor H has made one complete revolution, the screw B''' has made ten, and the arm B''' has traveled toward the front as far as it will go and must 70 be brought back. This is done by turning the arbor H backward by means of a key applied to the rear end, releasing the detent K for each notch “5” and rewinding the spring H''' at the same time. The indices at the front and 75 back show the number of stamps used, the rear showing the tens and the front the units. Thus, for instance, when the sheet S is placed on the cylinder the hand H' stands at “9.” The first strip is then pushed on the disk C, 80 requiring a turn of one notch of the arbor H, bringing the finger H' to “0,” at which point it remains while the first strip is being used, the numerals exhibited in the perforation b⁵ showing the number used off the strip. The 85 stamps are affixed to envelopes and other objects on the table T, Figs. 3, 4, and 6, adapted to slide longitudinally and supported upon a downwardly-yielding frame N. (Shown in 90 Figs. 1, 4, and 6.) Said frame consists of two 95 pairs of curved legs n, each pair connected at the lower and inner ends by a cross-piece n', near the upper ends by a cross-piece n'', and between the two by a rod n''', which latter is journaled to the base A by staples n⁴ or other 100 means at opposite and outward inclinations, the legs being approximately end to end. A strong plate-spring N' for each pair of legs is secured to the base and extends over the rod n''', 105 pressing at its end upon the lower cross-piece n'. The upper ends of each pair of legs carry an axle n⁵, with a pair of rollers n⁶ near each end. Upon these rollers the table T travels, being guided by flanges t at the bottom bearing against the outer edges of the legs, as 110 shown in Fig. 6. At the rear edge of the table, which extends well (at least half the size of the stamp) beyond the center line of the disk C, is an upwardly-projecting gage-flange t', extending in length over the outer end and 115 being stopped at a point where the table is required to pass under the disk C. About in line with the said gage-flange, occupying the inner end of the table, but only slightly raised above its surface, is a spring-knife T', adapted 120 to cut off a single stamp from a strip by striking transversely against the edge of the disk C from below.

The letter, envelope, or other object to which a stamp is to be affixed is placed upon the 125 table against the gage t' and the latter is rolled under the disk C. While the letter and

table are being so held, the lever E is pulled by the handle e', causing also an inward and outward sweep of the brush g', thus moistening that part of the object to which the stamp is to be affixed. The return of the lever E turns the disk C one space and projects a stamp from between its lower surface and the apron F under the center of the disk and over the moistened space of the object. The table 10 is now depressed and allowed to react with full force. The object is thus pressed upward against the projected stamp and the bottom of the disk, causing the stamp to adhere to the object and to be separated from the strip by the knife T'. When the strip is first cut from the sheet, the lever E must be pulled several times in order to advance the first stamp sufficiently, so that the next pull 15 will bring it in position to be affixed.

20 I claim as my invention—

1. In a stamp affixer, the combination of a stationary cylinder adapted to hold on its shell a sheet of stamps, a gage on one side adapted to receive the edge of the sheet, a 25 circumferential gage adapted to slide longitudinally, an arm secured to said gage projecting through a slot in the shell into the interior of the cylinder, means of propelling said arm intermittently forward and backward, a spring retracted knife journaled at the center of the cylinder and operating at the front edge of the shell thereof, a disk journaled at the center and front end of said cylinder and having its edge level with said 30 shell, means of rotating said disk intermittently a certain measured space, a short endless apron running over a roller at each end and pressed against the edge of said disk and extending near its center line at the bottom, a lever pivoted near the center of the disk and having its lower end bent to sweep close to the edge thereof and provided with a sponge or brush, a sliding table supported upon a spring frame and provided at its rear 35 edge with a knife adapted to extend across the edge of said disk and a spring frame supporting said table and jerk it upward against the lower part of the edge of the disk, substantially as set forth.

40 2. In a stamp affixer, the combination of a stationary cylinder adapted to carry upon its shell a sheet of stamps, a gage on one side of said cylinder adapted to receive the edge of said sheet, a circumferential gage adapted to receive the rear edge of said sheet and means of moving the same intermittently, a rotary disk of the same diameter as the cylinder and journaled upon a stationary bearing formed by the extended central part of the front end 45 of the cylinder, a stationary plate parallel to the face of said disk to which said extended central part of the cylinder end is secured, a knife blade journaled upon said extended central part of the front end of the cylinder 50 between said end and the rotary disk and having in its hub a spring adapted to return

said blade after being drawn forward, a series of pins projecting from the face of said disk and each pressed against said stationary plate by a spring at its rear said springs being equidistant from the center of the disk and from each other and each adapted to engage a perforation in said stationary plate, a lever journaled upon the extended central part of the cylinder end and having in its hub a spring 70 tending to rotate it and provided with a cam adapted to retract the engaged pin and by it turn the disk until another pin engages said perforation, an arm pivoted to the outer face of the stationary plate and having its lower 75 part made tubular and the end bent across the edge of the disk and perforated and provided with the sponge or brush and having its upper end connected by a link to the spring actuated lever and a short endless apron passing over two rollers journaled in a frame or casing carried and pressed against the edge of the disk by a spring, substantially as set forth.

80 3. In a stamp affixer, the combination of a stationary cylinder having a slotted shell, a shaft journaled in the ends thereof, and having the portion between said ends screw threaded, an arm extending through the slot in the shell provided with a threaded hub 85 adapted to travel upon said screw shaft, a gage extending partly around the shell of said cylinder and being secured to the projecting end of said arm, and means of rotating said screw intermittently a certain measured part, 90 substantially as set forth.

95 4. In a stamp affixer and recorder, the combination of a stationary cylinder having a slotted shell, a screw journaled therein, an arm with threaded hub upon said screw and extending through said slot, a pinion at the end of said screw, a wheel gearing in said pinion, a spring coiled upon the arbor of said wheel tending to rotate the same, a notched disk upon the arbor, a spring detent adapted 100 to engage the notches of said disk, a lever adapted to lift said detent, a pusher or presser guided by a pin in a slot near the top and by a pin below and pressed against the latter and upwardly by a spring on the opposite side and 105 having a wedge shaped projection adapted to pass against said lower guide pin and deviate said presser sidewise and cause it to slip off the end of the lever after having depressed and lifted the other end sufficiently to disengage the detent from one of the notches, an index or pointer at the end of the arbor and a dial face, substantially as set forth.

110 5. In a stamp affixer and recorder, the combination of an arbor H carrying a hand or 115 pointer and passing through a dial plate, a spur wheel h secured to said arbor, a spring H" tending to rotate said wheel, a notched disk h" secured upon said arbor, a hooked spring detent K adapted to engage the notches 120 of said disk, a lever L adapted to lift said detent out of engagement, and a presser M hav-

ing slot m and incline m''' and guided by the pins m' and m'' and lifted and guided by the spring M' and adapted to engage depress and slip off that end of the lever L which is not in contact with the detent, substantially as set forth.

6. In a stamp affixer and recorder, the combination of a stationary cylinder adapted to carry a sheet of stamps upon its shell, a disk 10 of the same diameter journaled upon the center of the cylinder at one end, a series of pins held slidingly projecting from the face of said disk and tending to engage a perforation in an opposite plate by the pressure of springs 15 when opposite the same in being turned, a pin secured to the projecting part of each of said pins at a right angle and bent backward and sliding in a perforation in said disk forming a guide, a lever journaled upon the same center as said disk and provided with a spring tending to turn said lever upon its bearing, a segmental finger secured to said lever wedge or cam shaped and adapted to press against the vertical parts of the guide pins and to cause them to retreat within said disk and then engage the pin so repressed by its broad heel and turn the disk by it and a stationary plate against which said spring pins bear and having a perforation adapted to be engaged 20 by all the pins in succession and stopping the rotation of the disk, substantially as set forth.

7. In a stamp affixer and recorder, the combination of a rotary disk journaled upon a stationary horizontal bearing, a stationary 35 plate parallel to the face of said disk, a series of pins slidingly held in said disk equidistant from its center and the end of each pressed against said plate by springs, a perforation in said plate adapted to be engaged by all the 40 pins in rotation, a pin secured to each spring pin at a right angle to form a shoulder in the projecting portion and bent at a right angle backward into the disk to form a guide, a lever journaled upon the stationary bearing upon 45 which the disk is journaled and having in its hub or drum a spring tending to rotate it, a segmental finger or cam on said lever narrow at the point and broad at the heel and adapted to bear on the shoulder of one of the 50 spring pins when drawn in the direction contrary to the pressure of the spring and causing it to retreat from the perforation in the plate and causing the disk to rotate when the heel of the cam engages it and the lever is 55 allowed to follow the action of its spring, substantially as set forth.

8. In a stamp affixer and recorder, the combination of a rotary disk journaled upon a stationary bearing, a series of spring actuated 60 pins projecting from its face equidistant from its center and equidistant from each other, numerals at the projecting ends of said pins, a stationary plate parallel to the face of said disk and having a perforation adapted 65 to be engaged by each of said pins in rotation by the action of their springs, means of disengaging the pin from such perforation

and tending to rotate said disk and a short endless apron running over rollers journaled in a frame pressed by a spring against the 70 edge of said disk, substantially as set forth.

9. In a stamp affixer, the combination of a rotary disk journaled upon a stationary bearing, a stationary plate parallel to the face of said disk and having a perforation adapted 75 to receive a pin, a series of spring actuated pins projecting from the face of said disk equidistant from its center and equidistant from each other and pressing by the action of their springs with their ends against said stationary plate and adapted to engage said perforation in rotation, a lever having its hub journaled upon the stationary bearing of the disk and having a spring tending to swing it in one direction, a cam on said lever adapted 80 to disengage the spring actuated pin from the perforation in the plate and push against the pin to cause the disk to turn upon its bearing, and an arm pivoted to the external face of the stationary plate and having its lower 85 end bent at a right angle across the edge of the disk and having the bent part and the part immediately above made tubular and the said bent part perforated and provided with a sponge or brush and its upper end connected 90 by a link to the upper end of the spring lever, substantially as set forth.

10. In a stamp affixer, the combination of a table having guide flanges at its lower surface, a gage flange at one end of its rear edge 100 and a spring knife at the other end, a spring support having rollers at its upper ends upon which said table may run and consisting of pairs of curved and inclined legs connected transversely and pivoted to the base and 105 having their lower ends held down by springs, substantially as set forth.

11. In a stamp affixer, the combination of two pairs of curved and inclined legs connected transversely and pivoted to the base 110 arranged with opposite inclinations and having their inner and lower ends held down by springs and the upper ends provided with rollers, a table having guide flanges at its lower surface, an upward projecting gage 115 flange at the rear edge at one end, a spring knife at the rear edge at the other end, a rotary disk journaled upon a stationary bearing parallel to the longitudinal motion of the table so that the rear edge of the latter may 120 pass transversely across its edge at the rear of its center line, means of rotating said disk and presenting the end of a strip of stamps under its center, a stationary plate parallel to said disk and an arm pivoted to said plate 125 and having its lower part made tubular and bent across the edge of said disk between it and the table and provided with a sponge or brush, substantially as set forth.

12. In a stamp affixer and recorder, the combination of a stationary cylinder adapted to carry a sheet of stamps upon its shell, a stationary gage along one side adapted to receive the edge of the sheet, a movable transverse

gage, covers B⁴ hinged to said cylinder at their lower edges and meeting at the top so as to completely envelop that portion of the cylinder containing the stamps and provided
5 with means of locking them to prevent interference with the stamps, substantially as set forth.

In testimony whereof I have signed in the presence of the undersigned witnesses.

JOHN KEITH.
